[57] CLAIM

The ornamental design of a drilling implement for setting beach umbrellas, as shown and described.

DESCRIPTION

FIG. 1 is a perspective view of a drilling implement for setting beach umbrellas, showing my new design;

FIG. 2 is a side elevation view thereof, with the handle disposed inside the tubular drill bit;

FIG. 3 is a top plan view of the design as shown in FIG. 1;

FIG. 4 is a front elevation view thereof, the view from the rear being identical;

FIG. 5 is a side elevation view, the view from the opposite side being identical; and,

FIG. 6 is a bottom plan view.
